United States Patent Office

Des. 203,413
Patented Jan. 4, 1966

203,413

DRILL

Paul O. Rawson, Trumbull, and George L. Schick, New Canaan, Conn., assignors, by mesne assignments, to The Stanley Works, New Britain, Conn., a corporation of Connecticut

Filed Dec. 2, 1964, Ser. No. 82,884

Term of patent 14 years

(Cl. D54—14)

FIG. 5

FIG. 6

FIG. 1 is a side elevation view of a drill embodying our design;

FIG. 2 is a front elevation view of a drill embodying our design;

FIG. 3 is a top plan view of a drill embodying our design; and

FIG. 4 is a rear elevation view of a drill embodying our design.

FIG. 5 is an elevation view of the side of the drill opposite to that shown in FIG. 1.

FIG. 6 is a bottom plan view of the drill.

The dominant features of the design reside in the portions shown in full lines.

We claim:

The ornamental design for a drill, as shown and described.
